Patented May 31, 1904.

UNITED STATES PATENT OFFICE.

THOMAS WILLIAM JOHNSON, OF NORTH ATTLEBORO, MASSACHUSETTS.

BRACELET.

SPECIFICATION forming part of Letters Patent No. 761,589, dated May 31, 1904.

Application filed October 9, 1903. Serial No. 176,433. (No model.)

To all whom it may concern:

Be it known that I, THOMAS WILLIAM JOHNSON, a citizen of the United States, residing at North Attleboro, in the State of Massachusetts, have invented a new and useful Improvement in Bracelets, of which the following is a specification.

My invention consists in the improved construction of a spring-bracelet provided with a covering of "woven wire," as hereinafter set forth and claimed.

In the accompanying drawings, Figure 1 represents a side view of the bracelet. Fig. 2 represents a top edge view. Fig. 3 represents a detail longitudinal section enlarged. Fig. 4 represents an enlarged transverse section. Fig. 5 represents the face view of a strip of flat woven wire from which the covering of the bracelet is formed. Fig. 6 represents an edge view of the same. Fig. 7 represents the transverse section of a woven-wire tube formed of the strips.

In the drawings, Figs. 5 and 6, A represents a flat strip of woven wire of which the outer covering of the bracelet is to be formed, a cross-section of a tube B, formed of the same by passing the strip A through the circular opening of a draw-plate, being shown in Fig. 7. The woven-wire tube B so formed is to be

divided into lengths suitable to form a bracelet and a flat spring C, made in bracelet form, of steel, German silver, or other suitable material, inserted therein, as shown in Figs. 3 and 4, the longitudinal seam D being arranged at the inner edge of the bracelet, so as to be hidden when the bracelet is held upon the wrist of the wearer. When the flat spring C has been inserted into the tubular woven-wire covering B, the connected parts are to be drawn through the circular opening of a draw-plate to slightly embed the edges *a a* of the spring C into the inner surface of the covering B, as shown in Fig. 4, thus preventing the turning of the covering upon the spring and maintaining the open seam D at the inner edge of the bracelet. Suitable knobs E E or other ornaments are attached to the ends of the spring to form a finish for the lapped ends of the bracelet.

I claim as my invention—

In a bracelet, the combination of the tubular woven-wire covering, drawn up from flat stock, and the flat spring within the covering, substantially as set forth.

THOMAS WILLIAM JOHNSON.
